UNITED STATES PATENT OFFICE.

CHARLES SALADINO, OF MIDDLE VILLAGE, AND JOHN CIRANKO, OF NEW YORK, N. Y.

SHOE-ARCH-SHAPING DEVICE.

Application filed October 5, 1927. Serial No. 224,079.

This invention relates generally to the manufacture of shoes, and has more particular reference to a novel shoe arch shaping device.

5 The invention has for an object the provision of a device of the class mentioned of simple durable construction, which is efficient in action, and which can be manufactured and sold at a reasonable cost.

10 The invention device consists of a U-shaped member having one of its arms formed with an elongated tapered aperture shaped to receive a shoe last, and the other arm has a clamping means associated therewith and provided with a forming block engageable against the last. One of the steps in a process of manufacturing shoes employing the invention device consists in 15 clamping the soles of a shoe between the last and the forming block, and allowing the same to harden in this position.

The forming block is removable from the clamping device, and may be replaced by differently shaped blocks, or adjustable blocks.

For further comprehension of the invention, and of the objects and advantages thereof, reference will be had to the following description and accompanying drawings, 30 and to the appended claims in which the various novel features of the invention are more particularly set forth.

Referring to the accompanying drawing, forming a material part of this disclosure:—

35 Fig. 1 is a face view of a device constructed according to this invention.

Fig. 2 is a plan view thereof.

Fig. 3 is a side view thereof.

40 Fig. 4 is a horizontal sectional view, taken on the line 4—4 of Fig. 1.

Fig. 5 is a vertical sectional view, taken on the line 5—5 of Fig. 1.

Fig. 6 is a perspective view of a forming block used in this invention.

45 Fig. 7 is a perspective view of another forming block used in this invention.

Fig. 8 is a perspective view of still another forming block.

50 Fig. 9 is a transverse vertical sectional view of still another forming block.

Fig. 10 is a fragmentary plan view of a shoe to which the invention device is applied, certain parts being shown in section, and other parts broken away to clearly 55 close the construction of the shoe.

Fig. 11 is a vertical sectional view, taken on the line 11—11 of Fig. 10.

The reference numeral 15 indicates generally a U-shaped member turned on its side so that arm 16 is at the bottom, and arm 17 at the top. The arm 16 is formed with an elongated tapered aperture 18 shaped to permit a flush sitting of the last indicated by dot-dash lines 19. The last is of customary construction being of two parts 65 indicated by split line 20. A strap 21 connected with the last, and passed through aperture 18 serves as a grip for pulling the last in place. The arm 16 is also formed with an aperture 22 positioned to accommodate a last pin 23 engageable with last 19 to hold same against displacement.

A wing screw 24 threadedly engages the arm 17, and has a ball member 25 formed at its lower end. A forming member 26 is 75 provided at its upper end with a cavity 27 in which ball member 25 engages. Locking plates 28 are secured to the top of form member 26, and serves to hold the ball member in the cavity. The bottom side 29 of the forming member is curved to a desired shape.

The forming member 26 may be used when the device is applied to a left shoe, forming member 26', with a bottom side 29' may be used for right shoes, and forming member 85 26^a with a bottom side 29^a may be used for either right or left shoes. The curved side 29 has one part more curved than the other, and curved side 29' is just opposite to this, while curved side 29^a is symmetrical at both 90 ends.

The modification of the invention illustrated in Fig. 9 discloses a forming member 30 arranged on the end of screw 24, and provided with an adjustable bottom side 31. 95 This is accomplished by having a movable portion 32 pivoted as at 33 to a stationary portion of the forming member. A screw 33 threadedly passes through the stationary portion and is engageable in apertures 34 in 100 the movable portions so as to lock the movable portion as desired.

The operation of the device consists in arranging the last as shown in Fig. 1, placing a shoe to be shaped thereon, and operating wing screw 24 to clamp the forming member against the shoe and last. The shoe thus placed must be in a wetted condition, that is, glue in the soles thereof must be undried as yet. After the glue 110

dries the shoe may be taken from the device.

Figs. 10 and 11 show a shoe to be placed on the last for the forming operation. This shoe consists of an outer sole 35, a reinforcing strip 36 secured to a shank 37, an inner sole 38 and shoe uppers 39. The dot-dash line 40 illustrates the outline of the shank before it is bent upwards. Glue 41 is placed around the strip 36 and between inner sole 35 and shank 37. This is the glue referred to in the previous paragraph.

While I have illustrated and described the preferred form, construction and arrangement of the several elements employed, it will be understood that the device is, nevertheless, susceptible of considerable modification therein, and I therefore reserve the privilege of resorting to all such changes as may be fairly embodied within the spirit and scope of the invention as claimed.

Having thus described my invention, what I claim as new, and desire to secure by United States Letters Patent is:

1. A shoe arch shaping device, comprising a U-shaped member, one of the arms thereof being formed with an elongated tapered aperture to receive a shoe last, and with an aperture to receive a last pin to hold the last against displacement, a wing screw threadedly engaged in the other arm, and a forming member connected to the screw and engageable against a last engaged in the said tapered aperture, the said connections between the screw member and forming member being a universal joint connection.

2. A shoe arch shaping device, comprising a U-shaped member, one of the arms thereof being formed with an elongated tapered aperture to receive a shoe last, and with an aperture to receive a last pin to hold the last against displacement, a wing

screw threadedly engaged in the other arm, and a forming member connected to the screw and engageable against a last engaged in the said tapered aperture, the said connections between the screw member and forming member being a universal joint connection and the forming member being shaped with a forming side.

3. A shoe arch shaping device, comprising a U-shaped member, one of the arms thereof being formed with an elongated tapered aperture to receive a shoe last, and with an aperture to receive a last pin to hold the last against displacement, a wing screw threadedly engaged in the other arm, and a forming member connected to the screw and engageable against a last engaged in the said tapered aperture, the said connections between the screw member and forming member being a universal joint connection and the forming member being shaped with a forming side adjustably arranged.

4. A shoe arch shaping device comprising a U-shaped member, one of the arms thereof being formed with an elongated tapered aperture to receive a shoe last, and with an aperture to receive a last pin to hold the last against displacement, a wing screw threadedly engaged in the other arm and formed with a ball member on its lower end, a forming member provided with a cavity at its upper end in which the ball member engages, the forming member being engageable against a last engaged in the said tapered aperture, and locking plates secured to the top of the forming member, for holding the ball member in the cavity.

In testimony whereof we have affixed our signatures.

CHARLES SALADINO.
JOHN CIRANKO.
